UNITED STATES PATENT OFFICE.

CHARLES FREDERICK BILLAU, OF CEDAR RAPIDS, IOWA.

FOUNTAIN-PEN.

1,162,557.

Specification of Letters Patent. Patented Nov. 30, 1915.

Application filed May 16, 1914. Serial No. 838,985.

To all whom it may concern:

Be it known that I, CHARLES F. BILLAU, a citizen of the United States, residing at Cedar Rapids, in the county of Linn and State of Iowa, have invented certain new and useful Improvements in Fountain-Pens; and I do hereby declare the following to be a full, clear, and exact description of the invention, such as will enable others skilled in the art to which it appertains to make and use the same.

My invention relates to certain new and useful improvements in fountain pens of the self-filling type and resides in the provision 15 of a novelly constructed pen which comprises self filling means that is simple as to construction, reliable and efficient in operation and cheap to manufacture.

An important object of my invention is to 20 provide filling means in which the operating rod is removable from the piston.

Another important object of my invention is to provide a piston that is slidable within the magazine barrel of the pen and formed 25 in such way that the piston rod when inserted into the barrel will readily find the screw threaded opening formed in the piston.

Another important object of my invention 30 is to provide novel means whereby the piston rod when withdrawn is freed from ink and prevented soiling of the fingers.

Another important object of my invention is to provide means whereby the packing 35 washer for the piston may be expanded.

Another important object of my invention is to provide a piston having a removable piston rod, said piston being provided 40 with a roughened surface arranged to coat with some part of the magazine barrel to prevent rotation of the piston while the rod is being unscrewed therefrom.

The invention further aims to improve fountain pens of the self-filling type so as to 45 render them much more practical, reliable and efficient in operation, light, strong and durable and cheap to manufacture.

The above and additional objects are accomplished by such means as are illustrated 50 in the accompanying drawings, described in the following specification and then more particularly pointed out as claimed.

With reference to the drawings, wherein I have illustrated the preferred embodiment 55 of my invention as it is reduced to practice, and throughout the several views of which

similar reference numerals designate corresponding parts: Figure 1 is a longitudinal sectional view taken through a pen showing my improved construction in assembled position. Fig. 2 is a fragmentary longitudinal sectional view showing more clearly the detail construction of my improved pen, and Fig. 3 is a cross sectional view taken on line 3-3 of Fig. 2 showing the roughened surface on the outer end of the piston head to prevent turning of the piston upon the unscrewing of the rod therefrom.

Referring to the drawings by characters of reference, the numeral 1 designates as an 70 entirety the magazine barrel of a fountain pen and that is attached in the usual manner at one end to the pen holding and feeding portion 2 of the pen which carries the pen point 3. The outer or other end of the 75 magazine barrel 1 is open and adapted to be closed by a frusto conical closure plug 4. This closure plug 4 is provided with a reduced cylindrical portion 5 at its outer end and said cylindrical portion 5 is disposed 80 in extended relation to the adjacent end of the barrel. A passage or opening 6 is formed longitudinally through the frusto conical closure plug 4 and at its outer end communicates with the concaved outer face 7 of 85 the cylindrical extension portion 5. The purpose of the concave portion 7 at the outer end of the cylindrical portion 5 will be later more fully described. Any suitable means may be employed for securely holding the 90 closure plug 4 within the barrel. The closure plug 4 is preferably formed of some suitable material such as rubber or the like. A cylindrical cap having one end closed and designated 8 is arranged to fit upon the portion 5 of the plug 4 and is disposed at its outer surface in flush relation to the barrel 1.

The pumping mechanism for filling the magazine barrel 1 consists of a piston head 9 as an entirety. This piston head 9 comprises a cylindrical body portion 10 that is provided adjacent one end with a central aperture 11 to receive the threaded end of a piston or pump rod 12. The aperture 11 extends about midway of the body portion 10. The end of the body portion 10 farthest removed from that in which the aperture 11 is formed is convex as at 13 and centrally of the convex portion is provided 116 with a screw threaded extension 14. A packing washer or ring 15 is mounted upon

the extension 14. A concavo convex washer plate 16 is mounted upon the screw threaded extension 14 and engages the lower or inner face of the packing ring or washer 15. A 5 nut 17 is turned upon the threaded extension 14 and forces the frusto conical washer 16 into engagement with the packing ring 15. The concaved face of the washer 16 is forced into engagement with the packing 10 ring 15 and the engagement of the packing ring 15 with the convex face 13 of the body portion 10 and concaved face of the washer 16 provides for the expansion of the packing ring 15 upon the screwing up of the nut 15 17. The rod 12 is provided at its outer end with a knurled or otherwise roughened knob 18 and is inserted through the plug 4 and at its inner screw threaded end is connected with the body portion 10 after the manner 20 previously described.

As a means for preventing the turning of the piston head 9 when it is desired to unscrew the rod 12, I provide a roughened surface in the form of corrugations, or projections 25 19 upon the outer face of the body portion 10 which is concaved as at 20. The concaved face 20 on the body portion 10 serves to properly guide the screw threaded terminal of the rod 12 when the rod is inserted into the magazine barrel 1 to be turned in the aperture 11 in the body portion 10 of the piston head 9. When it is desired to unscrew the rod 12 the body portion 10 is positioned with the projections or 30 corrugations 19 in engagement with the inner end of the plug 4. The projections 19 grip the inner end of the plug and serve to hold the piston head 9 against rotation.

It will be readily seen that should any 40 ink get between the piston head 9 and plug 4 there is possibility of its oozing out through the opening or passage 6 formed in the plug 4. The closure plug 4 in being provided with a concaved face 7 at one end and 45 of resilient material serves to prevent the soiling of the fingers, that is the withdrawal of the rod with ink thereon. It will be readily seen that through the medium of the plug 4 ink will not be gotten upon the 50 fingers from the rod 12 after the withdrawal of the rod. It will also be noted that by moving the piston head 9 up and down within the magazine barrel the feed passage of the pen is cleansed by such action. The 55 piston acts to force any matter clogged in the feed passage in being moved back and forth in the magazine holder 1. It will be

readily seen that the rod 12 may be completely removed with relation to the pen and ink cannot get beyond the piston head 60 9 thus insuring against soiling of the hands due to leakage of the ink. The concaved portions 20 and 7 provide for the proper guiding of the rod 12 when the rod is to be inserted into the barrel 1. 65

It will be readily seen with reference to the foregoing description and accompanying drawings that I have provided a simple and inexpensive pen which is reliable and efficient in operation and cheap to manufacture. 70

One of the most essential points of my invention is the fact that rod 12 may be readily removed entirely with respect to the pen and without in any way interfering 75 with the pen performing its proper function. It will also be readily seen that the rod 12 may be properly inserted for pumping operation in a most reliable and expeditious manner. 80

In practice, I have found that the form of my invention, illustrated in the drawings and referred to in the above description, as the preferred embodiment, is the most efficient and practical; yet realizing that the 85 conditions concurrent with the adoption of my advice will necessarily vary, I desire to emphasize the fact that various minor changes in details of construction, proportion and arrangement of parts may be resorted to, when required, without sacrificing any of the advantages of my invention, as set forth. 90

What is claimed is:—

In a fountain pen, a magazine barrel, a 95 relatively soft plug inserted in one end of said barrel having a tapered inner end extending a distance into said barrel, a piston slidably mounted within said barrel and having a concave end for engagement with the tapered extremity of said plug, a piston rod detachably connected with said piston, and corrugations or projections formed on the concave surface of said piston adapted to engage the inner tapered end of the relatively soft plug to prevent rotational movement of the piston during removal of the detachable piston rod. 100 105

In testimony whereof I affix my signature in presence of two witnesses.

CHARLES FREDERICK BILLAU.
